UNITED STATES PATENT OFFICE.

RALPH N. PITCHER, OF MILWAUKEE, WISCONSIN.

FLY-SCREEN.

1,139,574.

Specification of Letters Patent. Patented May 18, 1915.

Application filed January 8, 1914. Serial No. 810,930.

To all whom it may concern:

Be it known that I, RALPH N. PITCHER, a citizen of the United States, residing at Milwaukee, county of Milwaukee, and State 5 of Wisconsin, have invented new and useful Improvements in Fly-Screens, of which the following is a specification.

My invention relates to improvements in fly screens and it pertains to that class of 10 screens which are provided with outlet openings at their upper ends for the escape of flies from the buildings where such screens are used.

Experience has proven that to be effective 15 in preventing flies from entering buildings through the escape openings of this class, it becomes necessary to close the front side of such opening, whereby light is prevented from passing through the upper end 20 of the same. The outlet passage of the screen is darkened and flies are thereby prevented from entering the building.

My invention is further explained by reference to the accompanying drawings in 25 which—

Figure 1 represents a front view of a screen provided with the preferred form of my improvement. Fig. 2 is a detail view of the screen shown in Fig. 1. Fig. 3 is a 30 detail of one corner of the screen drawn on line $x-x$ of Fig. 2. Fig. 4 is a front view, and Fig. 5 is a top view showing a modified form of bracket for supporting the top of the screen at intermediate points between the respective sides of the frame, and Fig. 6 represents a modified form of screen in which the supporting brackets shown in 35 Figs. 1, 2, 4 and 5 are dispensed with and the upper end of the screen is supported at 40 a slight distance in front of the screen frame.

Like parts are identified by the same reference numerals throughout the several views.

1, 1 represent the side members of the frame.

2 is the bottom member.

3 is the top member. The top member 3 may be made of uniform thickness throughout 45 its entire length, as shown in Figs. 2 and 5, and secured to the upper end of the side members 1, 1 by a plurality of nails or screws 4.

5 represents a wire screen cloth of ordinary construction which is secured to the sides and bottom of the frame by a plu-

rality of tacks 6. By thus forming the top member 3 of the frame of uniform thickness throughout its entire length, an open space 7 is provided between such frame 60 member and the screen 6 through which flies are free to escape from the building where such screens are used.

8 is a flat thin strip of metal, or other equivalent material, which is preferably 65 made about the width of the frame member 3 and the same is secured at its respective ends to the side member 1 by a plurality of nails or screws and extends from one of said side members to the other. The 70 object of the flat strip of metal 8 is two-fold. First it serves as a support for the screen between the two vertical side members 1, while it also darkens the outlet passage at the upper side of the screen, whereby 75 flies are prevented from entering the dwelling where such screen is used through the darkened passage beneath the strip 8. The strip 8 is preferably provided with a plurality of rearwardly extending bends or 80 brackets 9 which contact with the frame member 3 and are adapted to be secured thereto with a plurality of screws 10 or in any other convenient manner. If desired, the rearwardly extending brackets 9 may be 85 replaced by angular brackets 11, which angular brackets 11 are preferably struck up and pressed out from said strip of metal, as indicated in Figs. 4 and 5, when the free end of such bracket is adapted to contact 90 with the top member 3. If desired, however, the strip supporting brackets may be separately made and thereafter secured in place by screws or in any other convenient manner.

By the form shown in Fig. 6, the rearwardly extending brackets 9 and 11 are dispensed with and an opaque strip 12 is bent forwardly so as to form an opening 13 in front of the upper rail 14 of the screen 100 supporting frame and the upper rail 14 is preferably made substantially of the same thickness as the side and bottom members of said frame.

It will be obvious that by the construction shown in said Fig. 6, the upper side of the screen supporting frame may be entirely covered with the window or sash without interfering with the escape of flies through the opening 13. It will also be 110 obvious that the member 12 when thus formed will support the upper end of the

screen at a slight distance from the frame, whereby flies are free to escape, as stated, through said opening 13. While the strips 8 and 12 are preferably made of metal, it is obvious that other opaque material may, if desired, be substituted therefor.

Having thus described my invention, what I claim as new, and desire to secure by Letters Patent, is—

10 In a device of the described class, the combination of a frame, a wire screen, a metallic opaque member adapted to partially inclose and darken an outlet opening

between the upper frame member and the upper edge of said screen and a plurality 15 of supporting brackets formed integral with said metallic member and interposed between said screen and the upper end of the screen supporting frame.

In testimony whereof I affix my signature 20 in the presence of two witnesses.

RALPH N. PITCHER.
